CAN BODY FORMING MACHINE

Walter E. Rooney, Bellingham, Wash., assignor to
 American Can Company, New York, N. Y., a
 corporation of New Jersey

Application October 25, 1941, Serial No. 416,580

6 Claims. (Cl. 153—32)

The present invention relates to an apparatus for shaping relatively flat can bodies into open tubular form and has particular reference to an apparatus for holding the flat body and filling it with air under pressure as an incident to reshaping the body into its desired tubular form.

The invention contemplates the reforming of previously flattened can bodies or the final shaping of can bodies which have been formed relatively flat as where the bodies are to be shipped before the bottom end is applied. Such reforming or shaping is done without an inside mandrel by the combined use of compressed air on the inside and forming molds which move in and surround the can body from the outside. By dispensing with an inside mandrel, flat or flattened can bodies having an inside enamel or other coating can be finally shaped without scratching or otherwise disturbing the coating.

An object of the present invention is the provision of a can body shaping apparatus which receives a flat open ended body and fills it with air under pressure so that the flat form is converted into cylindrical or other tubular shape.

Another object of the invention is the provision of an apparatus of the class described having forming molds for surrounding the flat body while it is expanded by internal air pressure so that the curved edges of the flat body are ironed out and the body wall is transformed into a uniformly smooth tubular body.

Yet another object is the provision of a flat body reforming machine having body engaging heads for holding the body as its open ends while air is introduced into the interior of the body and while the body is formed further by surrounding forming molds, such an apparatus also having air valve control for first introducing the compressed air into the end of the flat body at a position removed from the center and after the flat body has been expanded for closing off the first air means and for then applying the air at the center of the body as the air and the forming molds iron out and make smooth the body wall.

Yet another object of the invention is the provision of an apparatus operable at high speed for operating on a succession of flat can bodies to reshape the flat body into cylindrical form by the combined use of compressed air applied to the inside of the body and of forming molds effective on the outside of the body.

Numerous other objects and advantages of the invention will be apparent as it is better understood from the following description, which,

taken in connection with the accompanying drawings, discloses a preferred embodiment thereof.

Referring to the drawings:

5 Fig. 1 is a sectional plan view of an apparatus embodying the present invention;

Fig. 2 is a transverse vertical sectional view taken substantially along the line 2—2 in Fig. 1 and showing a flat can body in position at the beginning of the reforming operation;

10 Fig. 3 is an enlarged plan sectional detail taken substantially along the line 3—3 in Fig. 2;

Fig. 4 is a front elevation of the parts illustrated in Fig. 3 as viewed from a position below 15 that figure;

Fig. 5 is a sectional detail taken substantially along the line 5—5 in Fig. 3;

Fig. 6 is a sectional view similar to Fig. 2 but illustrating the can body at the completion of 20 the forming operation;

Fig. 7 is a transverse sectional view taken substantially along the broken line 7—7 in Fig. 1;

Fig. 8 is a transverse sectional detail taken substantially along the line 8—8 in Fig. 1;

25 Figs. 9 and 10 are plan sectional views similar to Fig. 1 but showing only that portion of the apparatus which is situated at the right and is in the center of that figure, Figs. 9 and 10 illustrating different positions of certain working parts; and

30 Fig. 11 is a transverse sectional view taken substantially along the broken line 11—11 in Fig. 9.

The working parts of the shaping or forming 35 apparatus embodying the present invention are contained for the most part within a two-part housing consisting of a base 21 (Figs. 1 and 2) and a cover 22. These two members are substantially square in plan section and are secured together at intervals by bolts 23.

At the center the cover housing 22 (Fig. 2) is formed with an opening 24 through which flat can bodies a having oppositely curved or rounded edges b are introduced into the machine. Directly beneath this position, the base 21 (see 45 also Fig. 6) is formed with an opening 25 through which reshaped or fully formed bodies c are discharged from the machine.

A magazine A (Figs. 2 and 6) is mounted upon 50 the cover housing 22 and extends down through the opening 24. Such a magazine comprises side plates 31 (see also Figs. 3 and 4) which are formed with inwardly projecting ledges 32. Ledges 32 are arranged in the four corners of 55 the magazine and provide guides for a stack

of the substantially flat can bodies *a*. The ledges 32 are extended down below the bottom of the side walls 31 in four stationary arms 35 (Figs. 1, 2, 3, 4 and 5) and each arm terminates in an inwardly projecting shelf or support finger 36. The shelf 36 is located just below the parting line of the housing members 21, 22. This shelf support determines the position of a can body during reshaping.

Provision is made for separating the lowermost flat body *a* from the stack of bodies in the magazine A. For this purpose cut-out devices are carried in part in the magazine and these devices support the entire stack at all times.

A pair of horizontal shafts 41 (see also Fig. 6) are carried in the side walls 31 of the magazine. Each shaft extends across one side of the magazine and between two of the ledges 32 on that side. The shafts are journaled for rotation in the spaced ledges.

Each shaft 41 carries a pair of starwheels 42 which are formed with sharp projecting teeth which project along the inner side into the magazine and beyond the inner wall of the adjacent ledge 32. Each ledge 32 is slotted as at 43 (Figs. 3 and 5) for the reception of an associated starwheel. Thus there are four starwheels and their teeth projecting into the magazine at the four corners provide support for the stack of flat bodies *a*.

The two shafts 41 rotate intermittently partially so that the projecting teeth of the four starwheels move down in unison. The entire stack of bodies is lowered with each such partial rotation. This rotation of the starwheels acts to cut out or separate the lowermost body *a* within the magazine and at the same time the remaining bodies in the stack are supported by other teeth of the starwheels.

The two shafts 41 are geared for uniform movement. One shaft 41 carries a gear 45 which is located just outside of one of the side walls 31 of the magazine. The other shaft 41 carries a gear 46 which likewise is located outside of the same side wall. Intermediate meshing gears 47 are rotatably mounted on studs 48 threadedly secured in the side wall 31. These gears 47 in turn separately mesh with gears 45 and 46 so that as the right-hand shaft 41 (Fig. 4), for example, turns in a counter-clockwise direction, the left-hand shaft 41 turns the same distance in a clockwise movement.

Provision is made for intermittently moving the shafts. For such purpose the gear 46, which is located upon the right-hand shaft 41, preferably is formed as an integral part of a ratchet wheel 51. A pawl finger 52 which is formed on one end of a rod 53, engages against a tooth of the ratchet wheel 51, as best illustrated in Fig. 4, and when the rod 53 is moved toward the left, this movement being equal to the length of one ratchet tooth, the shaft 41 is rotated counter-clockwise the distance of one ratchet wheel tooth.

The rod 53 reciprocates back and forth and on its rearward stroke (toward the right in Fig. 4), the pawl end 52 slides back over the tooth of the ratchet wheel and engages into the next tooth. The opposite end of the rod 53 is connected to an eccentric strap 54 (Figs. 1 and 3) which operates over an eccentric 55 mounted upon a horizontal crank shaft 56.

The moving parts of the apparatus are operated through a drive shaft 65 (Fig. 1) which is journaled in a bearing 66 formed at one side in the cover housing 21, 22 and in a bearing 67 car-

ried on a bracket 68 (Fig. 7) which is mounted on the base housing 21. The crank shaft 56 is journaled in bearings 71 (Fig. 1) mounted on the base 21. This shaft at the end opposite to the eccentric 55 carries a bevel gear 72 which meshes with and receives rotation from a pinion 73 carried by the drive shaft 65. In this manner the crank shaft 56 is rotated continuously during operation of the machine.

10 A second crank shaft 75, which is a substantial duplicate of crank shaft 56, is mounted on the opposite side of the machine and is carried in bearings 76 mounted on the base 21. The shaft 75 is geared to the drive shaft 65 so that its rotation is in unison with the rotation of the crank shaft 56. For this purpose shaft 75 carries a bevel gear 77 which meshes with and is rotated by a pinion 78 carried on the drive shaft 65.

As the shafts 41 in the bottom of the magazine 20 A move to release the lowermost can body *a* from the bottom of the stack the separated body drops down upon the support fingers 36. It will be observed by reference to Fig. 2 that the curved edges *b* of the can body rest upon the support fingers 25 so that the can body when in this dropped position is supported at its rounded edges.

Provision is made for clamping the flat can body in position on the support fingers 36. For this purpose clamping fingers or arms 81 (Figs. 30 1, 2 and 6) are designed to cooperate with the support ledges 36 to hold a can body in clamped position. Two of the clamping fingers 81 are mounted upon a horizontal shaft 82 (at the right in Fig. 2) and two other fingers (at the left) are 35 mounted upon a horizontal shaft 83. The shaft 82 is journaled in brackets 85 supported upon the base 21 of the machine. In like manner shaft 83 is journaled in bearings 86 which are also carried by the base.

40 The two shafts 82, 83 are interconnected for uniform oscillation and are moved in opposite directions. At the time a can body *a* is separated from the stack within the magazine and 45 when it falls to the supporting ledges 36, the fingers 81 are in raised position and out of the path of travel of the falling body.

After the body has come to rest upon the support fingers, the shafts 82, 83 oscillate in unison so that the fingers 81 carried on the shaft 50 82 are moved in a counterclockwise direction (Fig. 2) to bring a projecting end 87 of the finger down into the interior of the magazine space and on top of the positioned can body just above its curved edge *b*. At the same time the fingers 55 81 on the shaft 83 move in a clockwise direction so that their projecting ends 87 move down into clamping position on the can body along its opposite curved edge. These fingers hold the can body preparatory to the reshaping operation.

The shaft 82 (Figs. 1 and 7) carries an arm 91 the outer end of which is pivotally connected at 92 to a connecting rod 93. In like manner the shaft 83 carries an arm 94 which is pivotally connected at 95 to the opposite end of the connecting rod 93. This linkage insures uniform oscillation of the shafts 82, 83, the position of the links being such as to provide for opposite rocking movement as will be evident.

The shaft 83 also carries an arm 96 which is pivotally connected at 97 to a connecting rod 98. The opposite end of the rod 98 is connected to an eccentric strap 101 which is mounted on 75 and operates with an eccentric 102 keyed to the

shaft 75. This insures timed action of the clamp-fingers 81.

When a flat can body *a* is held in clamped position by cooperation of the support fingers 36 and the clamping fingers 81, the body is disposed between a pair of head members 111 (Figs. 1 and 9). Each can body head member is formed as a rectangular block (as best illustrated in Fig. 2) which is carried on the inner end of a head sleeve 112. A cap end 113 (see also Fig. 11) is screwed to the end of each sleeve 112. The sleeve 112 is mounted for slight longitudinal movement in a split bearing in the upper end of a bracket 114. The bracket 114 is preferably an integral part of the base 21.

The cap end 113 of each head member carries a pair of slide rods 115 which project outwardly and loosely fit within a bracket 116 formed on the base 21. A compression spring 117 is mounted on each slide rod 115 and is interposed between the outer face of the cap end 113 and the bracket 116. The two springs for each head 111 have a tendency to press the associated head toward the inside of the magazine A. This provides a yielding means for causing the two head members yieldingly to engage the open ends of the can body when it is time to begin the reforming operation.

At the time a can body *a* first is cut out from the stack in the magazine, the two head members 111 are in separated position, being held outwardly against the yielding action of the springs 117. This is the position illustrated in Fig. 9. A wedge ring 121 is provided for holding this position. The ring 121 is mounted on the sleeve part 112 of the head member and is interposed between the outer end of the bracket 114 and the cap end 113 of the sleeve.

Ring 121 is adapted for slight rotation on the sleeve and in one position the ring presses outwardly against the cap end of the sleeve to hold its corresponding head 111 in the outer position of Fig. 9. For this purpose the wedge ring 121 is formed with a projection 122 (Figs. 9 and 10) which in the position of Fig. 9 presses against the head and holds the springs 117 under compression. The inner or engaged face of the cap end 113 is formed with a notch 123 which at such a time is out of registry with the projection 122 on the ring.

When the wedge ring 121 is rotated on the sleeve 112 so that its projection 122 moves into alignment with and enters into the slot 123 the springs 117 press the head member parts 111, 112 and 113 toward each other and the inner face of the two heads engage the open ends of the can body as in the position of Figs. 1 and 10.

Rotation of the wedge ring 121 is effected in the following manner. Each wedge ring projects outwardly in an arm 126 which is pivotally connected at 127 to a connecting rod 128 (Figs. 1, 9 and 10). The opposite end of each connecting rod 128 is pivotally connected at 129 to an arm 131 (see also Fig. 8) which is secured to and which projects upwardly from a horizontal shaft 132. Therefore there are two of the arms 131 carried on the shaft 132, one for each of the can body head members. The shaft 132 is journaled in brackets 133 formed on the base 21.

The shaft 132 is oscillated in proper time to rotate the two wedge rings 121 so that the two can body head members 111 are released from their outwardly held positions and when released clamp the flat can body at its open ends.

For this purpose the shaft 132 carries an arm 135 which is pivotally connected at 136 to a connecting rod 137. The opposite end of the connecting rod is joined to an eccentric strap 138 which surrounds and is operated by an eccentric 139 carried on the crank shaft 75.

The admission of compressed air into the flattened can body *a* is controlled by a valve mechanism located in part in each head member 111. Each sleeve 112 is formed with a central bore 145 (Figs. 1 and 9) and a valve member 146 has sliding movement within this passage. The bore 145 is enlarged adjacent to but spaced inwardly from the inner face of each head member where it provides an air receiving chamber 147. The chamber in each head is in constant communication with a source of compressed air, a nipple 148 (Figs. 2 and 6) being threaded in the bottom of the head and opening at the top into a vertical port 149 cut in the head and joining with the chamber 147. The nipple is connected with an air hose 150 which leads from a suitable source of compressed air.

Near the inner end each valve member 146 (Figs. 1 and 9) is of less diameter as in a connection stem 151, the inner end of the valve rod constituting a valve head 152. When the two head members 111 are in separated position as when a flat can body drops from the magazine, the valve rod and valve head are in the relative positions shown by Fig. 9. The valve head 152 at such a time closes the inner end of the bore 145 and the valve stem 151 extends across the chamber 147. Compressed air is maintained in this chamber at all times during operation of the machine, but owing to the position of the valve now being considered, this air is not allowed to escape from the chamber.

Each head 111 (Figs. 2 and 9) is formed with a pair of horizontal ports 155 which terminate in the inner face of the head. These two ports are in the plane of the axis of the sleeve 112 and are spaced on opposite sides of the center of the head so that they are just inside of the curved edges *b* of the flattened can body *a* as it is held in clamped position on the fingers 36. When the heads 111 move into engagement with the open ends of the flattened can body these ports 155 then are in position at the open ends of the body to lead air into its interior.

Each port 155 connects with a chamber 156 formed in the sleeve 112. The chamber 156 is disposed in the rear of the chamber 147. The connection between ports 155 and the chamber 156 is made by means of zig-zag or angular passageways 157 cut in the head, a passageway being arranged on each side of the center of each of the heads.

After the heads are in clamping position against the flattened can body, the two valve members 146 are moved back, such a position being illustrated in Fig. 10. In this position the valve head 152 still closes the opening in the face of the head member 111. The valve stem 151 of each valve member now straddles the space between chambers 147 and 156 so that air passes from the chamber 147 around the stem and into the chamber 156. From this latter chamber the air separates into the two passageways 157 of each head and discharges through the spaced ports 155 into the flattened can body.

This compressed air entering into the interior of the flattened body from opposite ends thereof quickly expands the body by forcing its flattened side radially outwardly, the curved edges *b* ex-

panding or opening out as the can body is transformed into a more tubular shape. This action draws the opposite curved edges of the flat body inside of and away from the ports 155. Air is immediately shut off by further movement of the valve members 146.

Each valve member as it moves back still further withdraws its head 152 from the opening in the center of the associated head member 111 and this head now closes off connection between the chambers 147 and 156. This latter position is illustrated in Fig. 1 and it will be observed that each chamber 147 is now open directly to the interior of the clamped can body. Air thereupon flows into the head member and quickly fills the can body, further expanding it and bringing it into its finally desired tubular shape. In the embodiment shown in the drawings this shape is cylindrical, the finished can body *c* being shown in Fig. 6.

Each valve member 146 extends back and outside of the cap end 113 of the associated head sleeve 112 where it is connected at 161 (Figs. 9 and 11) to a link 162. The link 162 is pivotally connected at 163 to the lower arm of a bell crank lever 164. This bell crank lever is mounted for oscillation on a stud 165 which is carried in the bracket 116.

The upper arm of each bell crank lever 164 is pivotally connected at 166 to a connecting rod 167 (see also Figs. 1 and 7). Each connecting rod 167 is pivotally connected at 168 to the upper end of an arm 169 which is secured to a horizontal shaft 171. Shaft 171 is journaled in brackets 172 carried on the base 21. By means of this connection oscillation of the shaft 171 is imparted simultaneously to both of the valve members 146 for the two heads 111 so that the air is introduced into the open ends of the can body as just described.

The shaft 171 is oscillated by connection with the crank shaft 56. For this purpose, shaft 171 carries an arm 175 which is pivotally connected at 176 to a connecting rod 177. The rod 177 is secured to an eccentric strap 178 which surrounds and operates with an eccentric 179 carried by the crank shaft 56.

At the time that air is first introduced into the clamped flattened can body *a* through the ports 155, a pair of shaping molds 185 (Fig. 2) are in separated position on opposite sides of the body, being in horizontal alignment therewith. Each shaping mold comprises a semi-circular forming head 186 formed on the inner end of a block 187. Each block 187 carries an outer horizontal pivot shaft 188 and an inner parallel pivot shaft 189. The outer end of each block is formed with a bifurcated head 191 (see also Fig. 1) and this head carries the pivot shaft 188. Each shaft 188 projects outwardly beyond the sides of the head and in like manner the pivot shaft 189 projects beyond the walls of the block 187.

The two shaping molds 185 are supported from above being hung on parallel arms 192 and 193 in such a way as to be movable in a horizontal plane. One pair of arms 192 is pivotally connected at their lower ends to the projecting ends of the shaft 188 of each shaping mold. In like manner a pair of arms 193 is pivotally connected at their lower ends to the projecting shaft 189 of each shaping mold.

Each pair of arms 192 swings on a horizontal pivot shaft 195 which is supported in brackets 196 depending from the top cover housing 22. In like manner each pair of arms 193 for the asso-

ciated shaping mold 185 is supported by a pivot shaft 197 which is carried in brackets 198 also depending from the cover housing.

As soon as the head members 111 are in engagement with the open ends of the flattened can body *a*, the shaping mold units 185 move inwardly, the while the can body is expanding under the action of the compressed air. The inward as well as the outward movements of the 10 shaping molds are crank movements, being brought about by the crank shafts 56 and 75. This feature will now be considered.

The crank shaft 56 is formed with a crank 201 and this is located centrally of the housing 21, 22. 15 A split crank head 202 is mounted on the crank 201 and is connected by a connecting bolt 203 to a head block 204. Block 204 extends into the bifurcated head 191 of one of the forming head blocks 187. The head block 204 pivots on the 20 associated shaft 188.

In like manner the crank shaft 75 is formed with a crank 205 and a split crank head 206 is mounted on the crank. This crank head threadedly engages a connecting bolt 207 which is 25 joined to a head block 208. The head block 208 is confined within the bifurcated end 191 of the other forming head block 187, being pivotally mounted on the corresponding shaft 188.

The shaping molds 185 under the action of 30 their respective cranks 201, 205 move inwardly from the position illustrated in Fig. 2 to the final closed position of Fig. 6. By the time the shaping molds come together, the can body is in its full tubular form and the curved edges *b* of the body 35 are ironed out by the combined action of the shaping molds and the compressed air on the inside of the body.

During the time the can body is being reformed from the flattened shape *a* shown in Fig. 2 to 40 the final shape *c* in Fig. 6, the body is held between the head members 111. These members being pressed against the open ends of the body under spring action prevent any displacement 45 of the body from between the heads. As soon as the flat body is transformed into a more expanded position, its curved edges *b* move out from their clamped position on the fingers 36. The clamping arms 81 then move back to withdraw the projecting ends 81 from their position 50 under the magazine. The closing shaping molds also assist in holding the expanded body in proper place during this reforming operation.

After the body has been brought into final 55 shape the shaping molds 185 separate and the head members 111 are also separated. This frees the formed body *c* which drops by gravity through the opening 25 at the base of the machine. At such time the body falls into a chute formed by 60 guide rails 211 (Figs. 2 and 6) which are bolted to the base housing 21 and which extend up through the opening 25 in the base. The shaping molds move back into fully separated position and all of the parts are thus restored for reception 65 of the next flat can body *a* as it is separated from the magazine.

It is thought that the invention and many of 70 its attendant advantages will be understood from the foregoing description, and it will be apparent that various changes may be made in the form, construction and arrangement of the parts without departing from the spirit and scope of the invention or sacrificing all of its material advantages, the form hereinbefore described being 75 merely a preferred embodiment thereof.

I claim:

1. In a machine for reforming flattened tubular can bodies into cylindrical shape, the combination of a magazine for holding a stack of substantially flattened tubular bodies, cut-out devices for separating a said body from the stack of bodies in said magazine to isolate said separated flattened body from said stack for an immediately subsequent reforming operation, a support for holding said separated body by engagement with its oppositely curved edges, means for introducing air under pressure to the inside of the flattened body while so held to radially expand the same, and shaping molds for engaging the outside of the expanded body while it is still under internal pressure to iron out the said curved edges and to form an even tubular can body wall.

2. In a machine for forming tubular can bodies, the combination of a support for holding a substantially flat tubular body by engagement with its opposite curved lateral edges, head members located on opposite ends of the held flat body for engaging the opposite open ends of the body to close off its interior, means for introducing air under pressure through a said head member into the closed off interior of the flat body to radially expand the same by internal pressure, shaping molds for engaging and surrounding the exterior of the body while it is being thus expanded, and means for moving said shaping molds radially inwardly to maintain the same in continuous engagement with said body while the latter is maintained under internal pressure to iron out the said curved edges and to form an even tubular can body wall.

3. In a machine for forming tubular can bodies, the combination of a magazine for retaining substantially flat bodies in horizontal position and in stacked formation, a support secured to said magazine for holding an individual flat body by engagement with its curved edges, cut-out devices for separating the lowermost body from the stack of bodies in said magazine so that the separated body falls onto said support, clamping fingers cooperating with said support for engaging the supported body at its curved edges, means for introducing air under pressure to the inside of the flat body to expand the same, and shaping molds for engaging the outside of the expanded body while it is still under internal pressure to iron out the said curved edges and to form an even tubular can body wall.

4. In a machine for reshaping substantially flat bodies having opposite sharply curved edges into tubular can bodies, the combination of head members for engaging the opposite open ends

5 of a flat body to close off its interior, a said head member having a central air passage and a pair of laterally disposed air passages which terminate in the engaging faces of the said members, means for passing air under pressure first through said pair of passages and thereafter through said central passage and into the interior of the engaged body to radially expand the same by internal pressure, shaping molds for engaging the exterior of the body while it is being thus expanded, and means for moving said shaping molds radially inwardly to maintain the same in continuous engagement with said body while the latter is maintained under internal air pressure to iron out the said curved edges and to form an even tubular can body wall.

20 5. In a machine for reshaping substantially flat bodies having opposite sharply curved edges into tubular can bodies, the combination of head members for engaging the opposite open ends of a flat body to close off its interior, each head member having a central air passage and a pair of air passages which terminate in the engaging faces of the said members, the end of each pair 25 of passages being spaced on opposite sides of the central air passage so that the terminal ends of each pair are located just inside of the curved edges of the engaged flat body, means for passing air under pressure through said passages and 30 into the interior of the engaged body to expand the same, a valve located in each head for controlling the flow of air so that it issues from said spaced passages when the body is flat and from 35 said central passage as the body is expanding, and shaping molds for engaging the outside of the expanded body while it is still under pressure to iron out the said curved edges and to form an even tubular can body wall.

40 6. In a machine for forming tubular can bodies, the combination of a support for holding stationary a substantially flat tubular body by engagement with its opposite curved edges, means for introducing air under pressure to the interior of the flat body to expand the same while said body is held substantially stationary on said support, shaping molds for engaging the exterior of the body while it is being thus expanded, and means for moving said shaping molds radially inwardly during the introduction of air into the 45 can body interior to engage the molds with the body wall and to hold the molds against the body while the latter is being altered into tubular shape under the action of the internal air pressure, whereby to iron out the said curved edges and 50 to form an even tubular can body wall.

55 WALTER E. ROONEY.
